UNITED STATES PATENT OFFICE

HENRY ELBERT WRIGHT, OF SPRINGFIELD, MISSOURI.

DESIGN FOR A WINDOW-SHADE AND CURTAIN-POLE FIXTURE.

SPECIFICATION forming part of Design No. 30,995, dated June 13, 1899.

Application filed January 23, 1899. Serial No. 703,179. Term of patent 7 years.

To all whom it may concern:

Be it known that I, HENRY ELBERT WRIGHT, a citizen of the United States, residing at Springfield, county of Greene, State of Missouri, have invented and produced a new and original Design for a Window-Shade and Curtain-Pole Fixture, of which the following is a specification, reference being had to the accompanying drawing, forming part thereof.

10 The figure is a view, partly in perspective, of a window-shade and curtain-pole fixture, showing my new design.

15 The leading or characteristic features of my invention comprise the unitary article as herein shown; and the design consists in the bracket-like figure having the screw-threaded portion at one end thereof in the same plane as

the top and a notch or recessed front portion at the other end. Intermediate of these is a U-shaped part, the inner side of which projects 20 slightly higher than the inner portion. The lower portion of the bracket is irregular in outline, as shown.

The letter L represents an inner recess.

Having described my invention, what I 25 claim as new, and desire to secure by Letters Patent, is—

The design for a window-shade and curtain-pole fixture, as herein shown and described.

HENRY ELBERT WRIGHT.
